United States Patent Office.

WILLIAM McMILLEN, OF MILAN, ASSIGNOR TO HIMSELF AND Z. KING,
OF CLEVELAND, OHIO.

Letters Patent No. 70,591, dated November 5, 1867.

IMPROVEMENT IN LIFTING-JACK.

The Schedule referred to in these Letters Patent and making part of the same.

TO ALL WHOM IT MAY CONCERN:

Be it known that I, WILLIAM McMILLEN, of Milan, in the county of Erie, and State of Ohio, have invented certain new and useful Improvements in Lifting-Jacks; and I do hereby declare that the following is a full and complete description of the same, reference being had to the accompanying drawings, making a part of this specification, in which—

Figures 1 and 2 are side views of the jack in different positions.

Figure 3 is a top view.

Like letters of reference refer to like parts in the views.

In the drawing, A A' represent the legs or standards of the jack, one of which, A, is longer than the other, and is also provided with a shoulder, b. The upper ends of these standards are connected together by means of the link B, which is secured to each leg by the screw-bolts a a'. C is a lever, which is secured to the opposite side of the legs, but by means of the same bolts a a'; the bolt a' connecting the lever to the leg A, and the bolt a to the leg A', as shown in fig. 3.

When the jack is to be used, it is placed in the position shown in fig. 1, the load resting on either one of the pins D in the leg A, as may be desired to raise the load more or less; then, by pressing on the lever, and pushing it down, the upper end of the leg A' will be lowered and the leg A raised, thus lifting the load, and the lever, when pushed down in this way, shown in fig. 2, serves as a lock to hold the jack in position. When the jack is in this position, shown in fig. 2, the end of the leg A' comes against the leg A, as indicated by the dotted lines e, fig. 2, and prevents it from being pushed or moved out of place, as the weight of the load on the leg A has a tendency to press and hold them together. When the jack is not in use it can be folded together, as indicated by the dotted lines E, fig. 1, thus taking up very little room, and is easily handled, being also cheap and durable.

What I claim as my improvement, and desire to secure by Letters Patent, is—

The arrangement of the legs A A', in combination with the lever C and link B, when pivoted or jointed in the manner substantially as described.

WILLIAM McMILLEN.
